CLAIM

The ornamental design for a mount for a firearm sight, as shown and described.

DESCRIPTION

FIG. 1 is a perspective view of a mount for a firearm sight showing my new design;

FIG. 2 is a side elevational view thereof;

FIG. 3 is a top plan view thereof;

FIG. 4 is a bottom plan view thereof;

FIG. 5 is an end elevational view thereof with the opposite end being a mirror image thereof;

FIG. 6 is an opposite side elevational view thereof;

FIG. 7 is a perspective view of a second embodiment of the design shown in FIG. 1;

FIG. 8 is a side elevational view thereof;

FIG. 9 is a top plan view thereof;

FIG. 10 is a bottom plan view thereof;

FIG. 11 is an end elevational view thereof;

FIG. 12 is an opposite side elevational view thereof;

FIG. 13 is a perspective view of a third embodiment of the design shown in FIG. 1;

FIG. 14 is a side elevational view thereof;

FIG. 15 is a top plan view thereof;

FIG. 16 is a bottom plan view thereof;

FIG. 17 is an end elevational view thereof with the opposite end being a mirror image thereof; and

FIG. 18 is an opposite side elevational view thereof.
